CLAIM

The ornamental design for an exercise tire, as shown and described.

DESCRIPTION

FIG. 1 is perspective view of a first embodiment of an exercise tire according to my new design;

FIG. 2 is a front view of the exercise tire of FIG. 1;

FIG. 3 is a rear view of the exercise tire of FIG. 1;

FIG. 4 is a right side view of the exercise tire of FIG. 1;

FIG. 5 is a left side view of the exercise tire of FIG. 1;

FIG. 6 is a top view of the exercise tire of FIG. 1;

FIG. 7 is a bottom view of the exercise tire of FIG. 1;

FIG. 8 is a perspective view of a second embodiment of an exercise tire;

FIG. 9 is a front view of the exercise tire of FIG. 8;

FIG. 10 is a rear view of the exercise tire of FIG. 8;

FIG. 11 is a right side view of the exercise tire of FIG. 8;

FIG. 12 is a left side view of the exercise tire of FIG. 8;

FIG. 13 is a top view of the exercise tire of FIG. 8; and,

FIG. 14 is a bottom view of the exercise tire of FIG. 8.

The broken line showing of portions of the exercise tire depicts environment and forms no part of the claim.

1 Claim, 14 Drawing Sheets
